UNITED STATES PATENT OFFICE.

ATWELL J. BLACKFORD, OF CLEVELAND, OHIO, ASSIGNOR TO AMERICAN STOVE COMPANY, OF ST. LOUIS, MISSOURI, A CORPORATION OF NEW JERSEY.

WICKLESS OIL BURNER.

1,423,302.

Specification of Letters Patent. Patented July 18, 1922.

Application filed August 31, 1921. Serial No. 497,208.

To all whom it may concern:

Be it known that I, ATWELL J. BLACKFORD, a citizen of the United States, residing at Cleveland, in the county of Cuyahoga and State of Ohio, have invented certain new and useful Improvements in Wickless Oil Burners, of which the following is a specification, reference being had therein to the accompanying drawing.

10. This invention relates to improvements in wickless oil burners and particularly of the blue flame type.

The wickless type of burners comprises a trough into which the oil is fed and a lighting member in the trough for heating it up. In this type of burner the height of the flame is controlled by controlling the depth of the oil in the trough.

Heretofore the height of the oil in the trough for regulating the flame has been controlled in two ways:

1. By means of a needle valve in the oil supply for feeding the proper amount of oil to the trough to regulate the amount of oil in the trough and thereby regulating the flame.

2. By providing a maintained oil level for the trough and raising and lowering the trough in respect to the maintained oil level or vice versa, thereby controlling the amount of oil in the trough and regulating the height of the flame.

In practice these two ways of controlling the oil to the trough and thereby regulating the flame, the regulation of the flame has been found not to promptly respond to the regulation of the oil in the trough, because the wall of the trough above the oil has become highly heated and the slight increase of

40 the oil therein striking the hot wall of the trough instantly produces excess vapor with a corresponding excess abnormal flame and it only finds its intended flame level as the increased oil cools the wall of the trough.

45 This has been found very confusing to the ordinary operator and has been a serious objection to the wickless stoves, and applies to both of the above ways of controlling the amount of oil in the trough. A reduction

50 of the flow of oil to the trough for decreasing the flame does not instantly respond because sufficient time must elapse to lower the oil level in the trough by consuming the oil therein after its flow thereto is cut off or 55 reduced, and this is particularly true where

the needle valve control is used, and to some extent is true when the raising and lowering of the trough is used.

The primary object of my invention is to provide means for regulating the flame of 60 the wickless oil burner, whereby the flame is instantly and correspondingly increased or reduced by the regulating means, and the control is effected in a manner entirely different from the two previously referred to 65 ways.

In the blue flame type of burner, to which my present improvement relates, there is a combustion section consisting essentially of concentric perforated tubes, between 70 which the vapor passes from the trough and is supplied with air through the perforations, whereby a blue smokeless flame issues at the top of the combustion section, as well known and understood to those skilled in 75 the art.

In my improvement I regulate the flame by raising and lowering the combustion section in respect to the upper end of the trough while maintaining it in all of its positions 80 in operative relation to the trough. By these means the flame is instantly increased or decreased corresponding to the raising and lowering of the combustion section, whereby the operator can regulate the amount and 85 height of the flame to a nicety and without any particular skill since there are no confusing and deceptive results such as occur in the two ways previously used for this purpose, as already explained. 90

In the accompanying drawings:

Figure 1 is a side elevation of a wickless blue flame oil stove embodying my invention.

Figure 2 is a vertical central section 95 through a wickless blue flame oil burner showing my improvement applied thereto.

Figure 3 is a relatively enlarged view of a wickless blue flame burner with my improvement applied thereto, the same shown 100 partially in side elevation and partially in central vertical section.

Figure 4 is a horizontal sectional view on the line 4-4 of Figure 3.

Figure 5 is a sectional view on the line 105 5-5 of Figure 3 looking upward.

Figure 6 is a detached perspective view of the rod for lifting the combustion section out of operative relation and exposing the lighting member to be lighted. 110

Figure 7 is an enlarged sectional view of one side of a wickless burner trough with my improvement applied thereto.

The accompanying drawings illustrate the 5 preferred mechanical expression of my improvement but variations and changes therefrom may be made by those skilled in the art without departing from the principle of my improvement and the spirit and scope 10 of my invention.

Referring now to the drawings in which similar reference characters denote the same parts, 1 is the frame of the stove, 2 a maintained level oil supply which is so well understood by those skilled in the art that 15 explanation thereof is unnecessary. An oil supply pipe 3 extends from this oil supply and is suitably supported in the frame 1. I have here shown two burners, A and B, 20 which are in communication with the supply pipe 3, but the number of burners is wholly immaterial to my improvement as will be readily understood.

In carrying out my improvement any desired form of wickless burner trough 4 may 25 be used. As here shown, this trough is of the narrow type and a suitable lighting member 5 is placed therein, the lower edge of the lighting member resting on the bottom of the trough and the upper edge thus extending a suitable distance above the top of the trough to be lighted.

This trough 4 is positioned in respect to the maintained oil level 2 so that the oil is 30 normally in the trough a proper height to produce a maximum flame. Communication between the trough and the supply pipe 3 may be accomplished in various ways without affecting my invention but as here 35 shown it is by means of a suitable hollow casting or head 7 which is suitably detachably clamped in communication with the supply pipe 3. A pipe 8 has its lower end in communication with the hollow head 7 and 40 its upper end 9 communicating with the bottom of the trough 4. This construction holds the trough 4 in fixed relation to the oil level 2, whereby the oil does not rise in the trough above the maintained oil level 2.

This hollow head 7 below the pipe 8 is provided with a valve seat 10 and an ordinary 45 needle valve 11 cooperates with the valve seat 10 for controlling the flow of oil from the supply pipe 3 through the casting 7 to the pipe 8 and by means of which the oil flow to the trough can be cut off entirely or turned on. In the construction here shown the valve 11 has an elongated stem 12 which passes through an elongated tube 13, the 50 lower end of the tube having an oil-tight connection with the screw threaded boss 14 of the hollow head 7 and preferably there is a stuffing box 15 at the outer end of the tube 13. The valve stem 12 passes through 55 the tube 13 a suitable distance and has at-

tached thereto a hand wheel 16 by which the valve stem and its valve are operated for opening and closing the valve seat 10. A suitable dial 17 is attached to the tube 13 and an index hand or pointer 18 is attached 70 to the hand wheel 16 and extends close to the dial 17. The dial 17 is provided in the form here shown with three indications, viz., "Out", which means that when the pointer 18 is at that point the oil is cut off and the 75 burner extinguished. The hand wheel 16 and its pointer 18 are rotated in the direction indicated by the arrow in Figure 1, and the dial also has the indication "Start" which means the position of the pointer for 80 starting the burner, and also the indication "Full" which means the position for the pointer when the burner is full. From this it will be observed that when the pointer is at "Start" there will be a free flow of oil for 85 the purpose of having the oil reach the trough to its predetermined height quickly for lighting purposes and then the pointer is preferably, though not necessarily, turned to "Full" which means that the oil will flow 90 to the burner sufficiently rapid to maintain it in the trough to the maintained level 2 of the supply. One object of opening the valve beyond "Full" is to enable the oil to flow rapidly through the trough for starting purposes and to enable the valve to be opened beyond "Full" even in operation, if for any 95 reason there should be an impediment of flow of oil to the trough caused by sediment or otherwise. The valve 10, however, is not 100 used for regulating the flame as will herein-after clearly appear.

Mounted above the trough 4 is a combustion section C. This combustion section is of a well known type for producing a blue 105 flame from the vapor generated at the trough 4. The combustion section here shown comprises an inner vertical perforated cylinder 19 and an outer perforated vertical cylinder 20 separated from the inner 110 cylinder to form a vapor and flame space 21. The lower ends of these cylinders are contracted in the form here shown, as shown at 23 and 24, though this particular construction forms no part of my present invention 115 and is not essential thereto. It only enables the use of a trough which is of a relatively smaller diameter than the greatest diameter of the combustion section. Straight combustion sections may be used for carrying out 120 my invention. It is usual in these combustion sections to provide perforated diaphragms at the upper and lower ends of the combustion section and these diaphragms differ in specific construction and may differ 125 in carrying out my improvement from that here shown without departing from my invention. As here shown there are two diaphragms 29 and 26 at the lower end of the inner cylinder 19 of the combustion section 130

and a perforated cap or top diaphragm 27. As stated, the particular construction and particular location here shown of these diaphragms are not essential to carrying out 5 my present improvement.

My present improvement consists in having the combustion section C vertically movable in respect to the trough 4. In carrying out my invention the upward movement of 10 the combustion section in respect to the trough lowers the flame and the downward movement of the combustion section in respect to the flame raises or increases the flame and this without any regard to the 15 amount of oil in the trough. The height of the oil may be the same as that indicated by the oil level 2 or it may be more or less than that point. Whatever may be the height of the oil in the trough the flame is raised and 20 lowered in my improvement by raising and lowering the combustion section in respect to the trough. It will, therefore, be understood in carrying out my invention the normal height of the oil in the trough may be the 25 same as the maintained level 2 which is preferably the case, or it may be less by the manipulation of the valve 10, but whatever may be the desired normal height of the oil in the trough the flame is raised and lowered 30 by raising and lowering the combustion section in respect to the trough. Therefore, in the preferred form of my invention the trough is in a fixed position while the combustion section moves in respect to it, but 35 my improvement as broadly considered would be carried out by the reversal of this operation, that is to say, the combustion section may be fixed and the trough raised and lowered in respect to the combustion section. 40 The mechanical expression here shown for having a relative vertical movement of the trough and combustion section while maintaining them at all times during the movement in operative relation consists in providing 45 a supplemental trough 4'. This trough 4' is slightly larger than the oil trough 4 and embraces it as shown. Its upper inner and outer ends are provided with substantially L shaped shoulders 28 and 25, 50 upon which the lower ends of the inner and outer combustion section cylinders 19 and 20 rest. These shoulders may be formed in any desired manner so far as my improvement is concerned. 55 The means here shown for raising and lowering this supplemental trough 4', and with it the combustion section, comprises a rod 30 which passes through a vertical socket 31 which extends laterally from the upper 60 end of the hollow head 7. A shaft 32 is journaled in this lateral extension 31 and has its inner end provided with gear teeth 33 that engage gear teeth or a gear rack 34 on the rod 30, while the outer end of the shaft 65 32 carries a suitable hand wheel 35 for turn-

ing it. By means of this hand wheel, its shaft gear and the rack 34 the supplemental trough 4' can be raised and lowered as will be readily understood. For the purpose of assisting and steadyng the vertical movement of the supplemental trough it is provided with a depending tube 36 which is here shown arranged at one side of the center of the bottom of the trough and this tube surrounds the oil conduit tube 8 and moves 70 up and down through a lateral arm 37 which extends from the socket 31.

Heretofore the upper end of the oil trough has been provided with lateral cylinders such as 28 and 29, upon which the 80 lower end of the combustion section is supported, whereby they do not have any vertical movement while maintaining operative relation with the trough. It is the common construction in this type of burner heretofore to lift the combustion section away from its seat, thus breaking this operative relation with the trough for the purpose of exposing the lighting member to be lighted, but this is not the relative vertical movement of the trough and the combustion section hereinbefore referred to and included in the appended claims. Wherever this term of vertical movement of the combustion section in respect to the trough or relative vertical movement of the trough and the combustion section is used in the appended claims it means a vertical movement while maintaining the operative relation of the trough and the combustion section. 95

This supplemental trough which maintains the combustion section in operative relation to the oil trough 4 in all of its adjustments as it moves up and down may 100 amply be considered in one sense as a vertical extension and contraction of the wall of the trough, since it raises and lowers the seats of the combustion section while maintaining them in operative relation to the trough, because these seats have heretofore 105 been a part of the trough, and my improvement would be carried out in a broad sense in a construction which had the walls of the trough 4 vertically extensible for raising and lowering the combustion section. 110

Where the construction of the supplemental trough for raising and lowering the combustion section to regulate the flame is used it is not practical to make a liquid type joint between the two troughs. Therefore, 115 any condensation of the very rich vapor at the upper end of the trough 4 would have a tendency to fall by gravity and find its way between these two troughs and drop therefrom, which would be objectionable. To 120 avoid this I provide the bottom of the supplemental trough 4' with a suitable number of perforations 38 which will provide an upward circulation of air between the two troughs sufficient to mingle with and carry 125 130

upward any condensed vapor that may be at the upper outer sides of the oil trough 4.

For the purpose of lifting the combustion section C out of operative relation with the trough 4 for the purpose of exposing the lighting member 6 to be lighted, I provide the usual vertical movable rod 39 which passes through the lower diaphragms and has its upper end adapted to engage some part 10 of the center of the combustion section C', which in this instance is a transverse rod 40 extending through the combustion section. The lower end of the rod 39 may be of any desired construction and as here shown it 15 has a lateral bend 41 carrying a disc 42 which will rest upon the supply pipe 3 and its lower extremity is bent laterally and carries a handle 43. By this construction the rod is normally held in the position 20 shown in Figure 2, while it can be raised to lift the combustion section and when raised can be supported in this raised position if desired by turning the rod so that its handle 43 will rest on the supply pipe 3.

25 By regulating the flame through the relative vertical movement of the combustion section and the trough, the raising and lowering of the flame instantly and correspondingly responds to the relative vertical movement of the trough and the combustion section, and there is not the confusing failure to respond to the adjustment that exists in the 30 adjustments of this type of burner as heretofore used.

35 It will also be understood from the foregoing description that my broad invention is not limited to the particular way of accomplishing the relative adjustment of the trough and the combustion section, while 40 maintaining the operative relation of the parts of the burner.

Having thus described my invention what I desire to claim and secure by patent is:

1. A burner comprising a trough, a combustion section seated above the trough with its lower end around the upper end of the trough, and the combustion section vertically adjustable in relation to the trough without disturbing its operative position to 50 the trough, for regulating the flame.

2. A burner comprising a trough, a combustion section seat at the upper portion of the trough, a combustion section having its lower end supported on said seat, and means 55 for relatively vertically moving the trough and said combustion section seat without breaking the operative relation of the combustion section to the trough.

3. A burner comprising a trough, a combustion section above the trough with its lower end around the upper end of the trough, the combustion section vertically movable in respect to the trough without breaking its operative relation with the up-

per end of the trough for regulating the 65 flame.

4. A burner comprising an oil holding trough, an oil supply therefor having a maintained level, and a combustion section vertically movable in respect to the upper 70 end of the trough without disturbing its operative relation to the trough for regulating the flame.

5. A burner comprising an oil trough, an oil supply therefor, a supplemental trough 75 embracing the oil trough, a combustion section carried by the supplemental trough, and means for moving the supplemental trough vertically in respect to the oil trough for regulating the flame. 80

6. A burner comprising an oil trough, a supplemental trough embracing the oil trough, a combustion section supported on the supplemental trough, the supplemental trough having a vertical movement in respect to the oil trough for the purpose described, and an air passage between the troughs. 85

7. A burner of the type described comprising an oil trough, a supplemental trough 90 embracing the oil trough, a combustion section supported on the supplemental trough, and means for moving one trough in respect to the other for regulating the flame.

8. A burner of the type described comprising an oil trough, a supplemental trough embracing the oil trough, a combustion section supported on the supplemental trough, a maintained level oil supply for the oil trough, and means for moving vertically one 100 trough in respect to the other for the purpose of regulating the flame. 100

9. A burner of the type described comprising an oil trough, a supplemental trough embracing the oil trough, a combustion section supported by the supplemental trough, an air passage between the walls of the troughs, and means for vertically moving one trough 105 in respect to the other for regulating the flame. 110

10. A burner of the type described comprising an oil trough, a supplemental trough embracing the oil trough, an air passage between the troughs, the supplemental trough having an opening in its bottom communicating with its air passage, a combustion section supported by the supplemental trough, and means for moving one trough in respect to the other for regulating the flame. 115

11. A burner of the type described comprising a stationary oil trough, an oil supply therefor, a supplemental trough, a combustion section supported by the supplemental trough, and means for moving the supplemental trough and with it the combustion section vertically in respect to the oil trough for regulating the flame. 120

12. A burner of the type described com-

prising an oil trough, an oil supply for the trough, including means for maintaining the oil in the trough at a predetermined level, a combustion section above the trough, means 5 for moving the combustion section vertically in respect to the trough without disturbing its operative relation with the trough for regulating the flame, and means located between the trough and the maintained oil supply for cutting off the oil to the trough.

13. A burner of the type described comprising an oil trough, a supplemental trough embracing the oil trough and vertically movable in respect thereto, a combustion section 15 carried by and movable with the supplemental trough and an oil supply passing through the supplemental trough and communicating with the oil trough.

14. A burner of the type described com-

prising an oil trough, a combustion section 20 thereabove, means for moving one of said members vertically in respect to the other for regulating the flame, and a maintained level oil supply communicating with the oil trough.

15. A burner of the type described comprising a stationary oil trough, a maintained level oil supply communicating with the trough, a supplemental trough embracing the oil trough, a combustion section supported by the supplemental trough, and means for moving the supplemental trough and the combustion section vertically together for regulating the flame.

In testimony whereof I hereunto affix my signature.

ATWELL J. BLACKFORD.
